FOLDING DUST PAN

Ruben G. Fernandez, 335 W. 47th St.,
Miami Beach, Fla. 33140

Filed June 9, 1966, Ser. No. 2,634

Term of patent 14 years

(Cl. D44—18)

FIG. 1 is a front elevation of a folding dust pan showing my new design.

FIG. 2 is a side elevation thereof.

FIG. 3 is a rear elevation thereof.

FIG. 4 is a top plan view thereof.

FIG. 5 is a bottom plan view thereof.

I claim:

The ornamental design for a folding dust pan, as shown.
